YARN SPOOLING MECHANISM

Edgar F. Hathaway, Wellesley, and Walter Bixby, Dorchester, Mass.

Application June 7, 1933, Serial No. 674,708

24 Claims. (Cl. 28—55.5)

The present invention relates to textile machinery and more particularly to mechanism such as spooling machines or so-called yarn setting frames, for the preparation of yarns for weaving, as in Axminster and other carpet or like looms. It aims to provide improved mechanism of the class and for the purpose described, and in which the accurate and rapid handling of the yarns and the conditioning of the machine are facilitated, together with other improvements which will be apparent from the accompanying description and drawings.

In the drawings, illustrating, by way of example, certain embodiments of the invention,

Fig. 1 is an elevation of a portion of a yarn spooler or setting frame embodying one form of the invention, viewed from the rear, that is, looking in the direction of yarn travel, and toward the spool, the transfer comb being in elevated position;

Fig. 2 is a vertical cross-section of the mechanism of Fig. 1;

Fig. 3 is a perspective view showing portions of one form of reed or separator;

Fig. 3^a shows the lower portion of one of the dents or elements of the reed of Fig. 3;

Fig. 4 is a vertical cross-section through that portion of the spooler or setting frame which includes the reed or separator and associated parts, including the holder for the transfer comb, yarn-end spacer or clamp, with the latter in raised or applying position, as in Figs. 1 and 2;

Fig. 5 is a partial rear elevation, with parts in vertical longitudinal section, upon a smaller scale, corresponding to the upper portion of Fig. 1, but with the comb in down or winding position;

Fig. 6 is a vertical cross-section through the mechanism of Fig. 5, showing also a yarn spool in winding position, and with the comb down, as during winding;

Fig. 7 is a plan view upon a larger scale of one end portion of the holder for the yarn-end spacer, transfer comb, or clamp;

Fig. 8 is a longitudinal vertical section through an end portion of said holder, showing a transfer comb in position therein;

Fig. 9 is an end elevation of the holder as shown in Fig. 7, looking from the left in said figure, with the comb stop omitted for clearness;

Fig. 10 is a plan of the reed and comb holder according to Figs. 5 to 9.

Figs. 11 to 16 illustrate certain modifications.

In said figures, Fig. 11 is a cross-section through the reed and comb holder portions of the machine, corresponding to Fig. 4, upon a larger scale,

the parts being in their raised or comb-applying position;

Fig. 12 is a partial rear elevation of the reed and the comb or end clamp as in Fig. 11;

Fig. 13 illustrates an alternative arrangement of the reed of Figs. 11 and 12, the comb holder being in down position;

Fig. 14 is a plan view, with parts omitted, illustrating the relative positions of a spool in winding position upon the machine and of the 10 yarns, reed and transfer comb;

Fig. 15 is a rear elevation of the reed and comb holder of Fig. 14, in down or winding position; and

Fig. 16 is a vertical cross-section of the mechanism of Fig. 15, also illustrating the down position of the parts, during the winding operation.

Referring first to Figs. 1 and 2, we have there shown a textile machine in which the improvements of our invention may be embodied, the machine illustrated being typical of so-called spoolers or yarn setting frames, for winding tufting-yarns onto a spool, in the desired pattern arrangement. In certain respects the improvements of our present invention are particularly adapted for use 25 with such machine. That shown comprises a frame 1 supporting a main or drive shaft 2 to which power may be applied as through the series of pulleys 3, Fig. 1. Suitable shipper mechanism 4 is provided including a shipper rod 5 and shipper 30 lever 6, Fig. 2, by which the operator may control the machine, to impart winding movement to a spool 7, in either direction at will, or to stop the machine.

The yarns, coming from bobbins (not shown) 35 are taken on to the spool 7, which is removably supported for winding movement, between releasable rotary members engaging its opposite ends and operatively connected with the drive shaft 2 through suitable gearing, including the pinion 8 40 and gear 9, Fig. 2. A series of friction rolls 10, 11, 12 engage the periphery of the spool in its winding position and are supported for bodily yielding movement away from the spool as the wound-on yarn builds up. The rolls are pressed 45 against the spool during its winding, so that the yarns are wound evenly and tightly and in the same order or pattern-arranged condition as is provided for the reed or yarn-separating device upon the machine.

To provide for such movement of the rolls, the upper friction roll 10 is carried on an arm 13 pivoted at 14 and having a hooked link 15 releasably engaged with its opposite end, said link being connected at its lower end to a weighted 50 55

5 pivoted lever 16. The rear friction roll 11 is mounted on a weighted arm 17, while the third roller 12 may be similarly movably supported. This positioning and releasing mechanism for 10 the friction rolls, by which they are pressed against the spool, during winding, and are adapted to be opened out or released from the spool, for removal or insertion of the latter, also includes a roll releasing shaft 18 having crank and link connection with a weighted lever 19 fulcrumed on the machine as at 20 and connected by a link 21 with the pivot 14 of the arm of the top roll. On the same releasing shaft 18 is a second arm 22 carrying a cam roll 23 on which rests the 15 weighted lever 16. Turning of the roll release shaft, in a counter-clockwise direction as viewed in Fig. 2, serves to open out the friction rolls, through the linkage system of which portions have been referred to above and appear in Fig. 2. 20 The yarns to be wound are passed through and separated by a reed or separator upon the machine, intermediate the bobbins or source of yarn supply and the spool. After winding of the spool, the yarn ends are held in the same spaced relation by a portable transfer comb, spacer or yarn-end clamp, the spooling machine having provision for supporting such spacer or clamp and for applying it to the yarns. These spacers or clamps, on completion of the winding operation, are temporarily attached to the respective spool so that 25 the latter may be removed and stored in quantities for subsequent use. It is with the yarn guiding and separating portions of the spooling mechanism, including the reed, the holder for the yarn-end clamp or transfer comb, and their 30 associated parts and operating means, both individually and in their relation to the machine as 35 a whole, that our present invention is mainly concerned.

40 Referring now to Figs. 1 to 10, there is provided at the upper rear portion of the machine, as seen at the left in Fig. 2, a cross piece 25 supported by brackets 27, 28 and carrying a yarn bar or platform 26. The yarns coming from the creel or 45 other yarn source pass transversely over the platform 26, through the reed or separating guide previously referred to, and thence to the spool 7.

The reed comprises a multiplicity of dents or elements 30 extending across the machine, over 50 the full width of any series of yarns to be wound, said dents and their mounting as herein illustrated being of novel construction.

55 As best seen in Figs. 3, 3^a and 4, the dents are of a general blade-like form, being stamped, cut or otherwise formed from suitable sheet metal or other material. Each comprises a main or body portion 31 preferably having a substantial extent in the direction of the yarn travel, so that relatively elongated yarn guide passages are provided between adjacent dents, as contrasted, for 60 example, with the mere separation afforded by a series of pins or pegs.

65 Each dent has a mounting portion or tang 32 whereby it is adapted readily to be mounted in fixed position, or to be individually removed. The dents are thereby detachably set in a mounting bar or element 33, herein including upper and lower flanges 34 and 35 having aligned series of slots or dent-receiving formations 36 and 37 respectively. The tangs of the dents, of reduced width, are adapted to be set into said vertically aligned receiving formations 36 and 37, and the body portions of the dents have each a shoulder 38 for seating on the upper flange, positioning 70 them vertically. As illustrated, the lower ends 75

of the dent tangs 32 are of further reduced width, as indicated at 39, providing a lower shoulder 40 adapted to seat on the lower flange 35, further positioning and supporting the dents. The two series of receiving formations 36 and 37, and the tangs or mounting portions 32 of the dents are preferably so proportioned that the latter have a supporting fit in said formations, with their rear edges 41 in engagement, or substantial engagement, with the mounting bar 33, so that they are 10 held against undue lateral movement in all directions.

Means is also provided for removably retaining the dents against unintentional upward withdrawal. For this purpose each dent tang 32 has 15 formed in it a notch 42 adapted to receive the lateral rib 43 of a detent 44 extending along the reed and suitably secured as by screws to the cross bar 25 or to a lateral extension 45 thereof. The detent 44 may be formed as one piece extending the full length of the comb or may comprise a number of sections, and it is preferably of sufficiently resilient material so that it may be sprung outwardly, to release any desired dent or a plurality thereof. The mounting bar 33 is itself detachably screwed or otherwise held in fixed position upon the cross bar 25.

20 The upper portions of the dents are preferably of a somewhat rounded and tapering form substantially as illustrated, to facilitate the initial 30 positioning of the yarns or yarn groups between them. The dents also are desirably equipped with means for preventing unintentional vertical upward escape of the yarns. For this purpose we have illustrated, see particularly Figs. 3 and 4, 35 a laterally deflected nib or barb 46 at an upper portion of each dent, each such element being offset from its dent, toward the next adjacent dent, so that it crosses or substantially crosses the interdental space. These barbs or lateral projections 46 prevent the yarns from escaping upwardly during ordinary use of the machine but permit them to be removed in that direction, by 45 intentional bending or deflecting of the yarn about the barb. The upper edges of the projections or nibs 46 are desirably inclined downwardly, as indicated at 47, to facilitate manual or other broadwise insertion of the yarns between the dents.

50 In combination with the described reed we desirably provide means for readily identifying any dent or any interdental space of the reed, as an aid to the initial setting up of the yarns and to facilitate the proper re-laying of a yarn which might become broken or whose supply runs out. 55 Accordingly we have herein illustrated a visual scale or index 48 set along the yarn bar 26 adjacent the reed. The scale may be provided with a series of graduations 49 corresponding either to the dents or to the spaces between them, these 60 graduations preferably being numbered, as indicated at 50, Fig. 3, in a readily readable manner serially across the reed, or through repetitive series such as one to ten, one to ten, etc., alternate of the numbers or other indicia being offset 65 as indicated to facilitate reading of the scale. In order also readily to distinguish or identify a particular dent of the reed or particular section thereof including a plurality of dents, we also may provide means for visually distinguishing or differentiating some of the dents, in a regularly recurring or other order, as, for example, every sixth dent, or by any other desired grouping thereof. As one convenient form of such 70 visually differentiating means we have illustrated 75

some of the dents, each sixth one in the particular arrangement shown, and also the outer dents of the reed, as provided with a marker or marking portion 51, herein projecting upwardly above the 5 main level of the reed, and clearly demarking the same into a plurality of sections or multiple dent units. These markers may also be individually distinguished by color means thereon, to correspond with the yarn color of the section of 10 dents marked by them, or otherwise. By reason of the demountable and readily assemblable individual mounting of the dents, including these marker dents, the position of the markers can readily be shifted or rearranged to suit different 15 pattern requirements.

As previously stated, the yarns when wound upon the spool then have their ends separably held in their position as wound, during subsequent handling and storage of the spool until it is to 20 be used in a loom. This is accomplished by means of a portable transfer comb or yarn-end clamp, one type of which is seen at 53 in Figs. 2, 4, 5, 8 and 10. The setting frame or spooling machine as herein shown includes means for holding such 25 transfer comb in proper position relative to the series of yarns, and for applying the comb to the yarns upon completion of the winding operation.

Such means herein includes a comb holder or 30 holder bar 54 formed with a U-shaped seat 55, see Fig. 4, for a comb. This comb holder is mounted upon the machine for vertical movement relative to the reed and to the yarns. In Figs. 5 and 6 it is seen in its normal or down position, while in Figs. 2 and 4 it is shown elevated to bring 35 the teeth of the comb supported thereon up between the series of yarns, for applying the comb to them. At its ends the comb holder 54 is guided for such vertical movement in ways formed in the vertical guides 56, 56 suitably mounted as 40 upon the cross bar 25; see particularly Fig. 10. The comb holder 54 may be accurately positioned and adjusted longitudinally as by means of an adjusting guide or block 57, one at each end, and 45 adjustably mounted on the holder as by means of the bolt and slot connection 58, Figs. 7 and 8. The outer end faces of the guide blocks 57 are adapted to have positioning engagement with the vertical guides 56, thus adjustably positioning the comb holder lengthwise.

50 A transfer comb such as seen in Figs. 4, 8 and 10 is positioned for application in the seat 55 of the holder. The transfer comb as here shown for the purposes of illustration is of the type to which a yarn retaining cap (not shown), is subsequently applied, the comb being equipped with clips 53a for securing such cap, and with attaching springs 53b for temporarily holding the transfer comb on and along a spool, the springs being engaged over the spool pintles. The comb holder, 55 for receiving this or other types of comb, as herein shown, is of a novel open-end construction facilitating cleaning of the parts. As best seen in Figs. 7, 8 and 9, the end portions of the U-shaped comb seat 55 are expanded laterally and also deepened below the general level of the bottom of the seat, forming a cleaning pocket 59. Outwardly beyond these pockets, of which there is preferably one at each end, the comb holder is slotted vertically, providing the open slot formation 60 as seen in Figs. 7 to 10. These formations enable the comb holder to be cleaned without removal from the machine, merely by brushing any collected lint or dirt along the bottom of the comb seat 55, into one of the end pockets 59 and thence 65

downwardly and outwardly through the adjacent end slot 60.

Means is also provided for adjustably positioning a transfer comb 53 in its holder, to bring it accurately into the desired position or alignment with respect to the reed. For this purpose we employ adjustable comb stops or blocks 61, located adjacent the ends of the comb seat and within the end slot 60 of the comb holder. These stops 61 may be variably positioned lengthwise of 10 the holder, as by means of the slot and screw connection 62, and are adapted to have end engagement with the comb, positively and accurately to position the latter longitudinally with respect to the holder and also in relation to the reed. 15

The comb holder with a transfer comb seated therein is adapted to be elevated at the desired time, for applying the comb to the yarns, manually or automatically. The lifting means here shown by way of example includes a plurality 20 of cam levers 63 pivotally hung as at 64 upon a front cross strip 65 extending between the vertical guides 56. The comb holder 54 seats upon the upper portions of the cam levers 63, and the lower portions of the latter are interconnected 25 as by a link 66. Operating rods 67 extend out to the side of the machine, preferably one at each side, whereby the cam levers may be swung in unison to elevate the comb holder, from its normal or lower position as in Figs. 5 and 6 to its upper yarn-applying position as illustrated in Figs. 1, 2 and 4. Stops 68 adjacent the cam levers limit the movement of the levers, in either direction.

By comparison of Figs. 5 and 6 with Figs. 2 and 4 it is apparent that the lifting of the comb 35 holder carries the transfer comb 53 up from its previous position below the path of the yarns, assumed during their winding, to its applied position. In so applying the transfer comb its teeth, see Fig. 8, are passed up between the yarns extending through the reed, so that the transfer comb then spaces the yarns and holds them in the desired distribution lengthwise the spool. The spool, yarns and transfer comb may then be removed from the machine, the transfer comb 45 being then attached to the spool, in the manner previously described, to retain the yarn ends in their proper distributed positions during handling and storage of the spool prior to use in the loom. Difficulty has heretofore arisen in applying transfer combs to the yarns, due to improper reception of the yarns in the comb and to splitting of the yarns or groups of yarns by the comb teeth, this being true whether the yarns or so-called "ends" are single strands, or, as more 50 usual, are composed of a plurality of strands or individual yarns.

This difficulty we have found to have been caused by inadequate positioning or guiding of the yarns during the comb applying operation, 60 and to the character of reed previously employed and the relatively large gap between the reed and the plane of comb application. From a consideration particularly of Fig. 4 it will be seen that in accordance with our invention the reed and 65 the comb applying elements are so constructed and arranged that the comb is applied while the yarns are positively held and guided by the reed dents 30, and at or substantially in the plane of the reed or its fore portion. It will be noted that 70 the lower portions of the blades 31 of the reed dents are recessed rearwardly as at 31a and that said guiding portions or blades 31 of the dents extend forwardly to or substantially to the plane of the comb, even, if desired, overhanging the 75

relatively narrow portion 54a of the comb holder between the comb teeth of the reed. This close juxtaposition of the comb and the reed becomes possible, without operative interference between them, by reason of the blade-like construction of the reed dents, with their extensive guide portions lengthwise of the yarns, and the general novel formation of said dents and of their special form of mounting, all as previously described.

Obviously our invention is equally adapted for use with a spooling machine or set frame equipped with means for automatically lifting and applying the transfer comb at the end of the winding operation, such for example as shown in the patent to Edgar F. Hathaway and Charles Lea, No. 1,313,294, of August 19, 1919, as well as in connection with the manual comb applying mechanism herein shown by way of example.

Referring now to Figs. 13 to 16, we have there illustrated a construction also embodying the principles of our invention as previously described in connection with the preceding figures, but which is particularly adapted for use in connection with the preparation of yarn spools for use in "wide" work, that is, where a plurality of spools are to be installed, in axial alignment, along one carrier or "tube frame," for use in wide looms. In such cases it will be understood that the adjoining heads of two spools, and the spool supports upon the yarn carrier or "tube frame," necessarily cause a gap between the yarn series as positioned upon the several spools. The yarn guiding passages or "tubes" of the yarn carrier, however, are uniformly spaced from end to end of the latter, so that in passing from the spools to these guide passages the yarns must be somewhat spread or fanned out, lengthwise the spools, as indicated by the dotted lines in Fig. 14. In such instances, the transfer combs employed are of a length differing from and generally exceeding that of the yarn series upon the spools, and have their interdental spaces distributed in uniformity with the yarn passages of the yarn carriers or "tube frames" with which the spools are to be employed. The construction of Figs. 11 to 16 is particularly adapted for use where a series of yarns or the like is to be wound upon a spool which may be of a different length from that of the transfer comb or yarn-end clamp, one of the reasons for such difference in length being that just stated. In other words, the pitch or distance between the yarns as upon the spool is different from the pitch of the yarn receiving portions or interdental spaces of the transfer comb. In said figures the yarn pitch of the spool is less than that of the transfer comb, but in some cases the condition may be the reverse. Parts otherwise not specifically referred to in connection with Figs. 11 to 16 may be similar as in the figures previously described.

Referring first to Fig. 15, the reed dents 70, or some of them, are formed with laterally offset portions, as contrasted with the straight dents of Figs. 1 to 10. The distribution and manner of offset of these dents is such that their upper portions 71, which function to guide the yarns during the winding thereof, are comprised within the yarn-receiving length of the spool and are spaced to distribute the yarns uniformly, or as desired, upon the spool. That is, these upper or winding-guide portions of the reed dents correspond to the guide-portions of the dents as in Figs. 1 to 10. In the present figures, however, provision is made for elevating the reed itself together with and in unison with the lifting of

the transfer comb, and the offset of the lower portions of the reed dents is such as to spread and distribute the yarn series to bring the yarn spacing into conformity with that of the transfer comb. A spooling machine embodying this broad principle is disclosed and claimed broadly in our previous Patent No. 1,666,650, dated April 17, 1928.

Still referring to Fig. 15 it will be understood that the reed dents 70 are offset, with the exception of the central dent or central series of dents, and are offset in opposite directions at the two sides of the central dent or dents. This offsetting is desirably by increments varying progressively from the central portion of the reed toward its ends so that, in the comb applying operation, the yarns are spread to the varying extents desired to bring them into the somewhat greater but uniformly spaced condition as required for the transfer comb; see the dotted line position of the yarns in Fig. 14. In the present illustration the offsetting of the reed dents is outwardly toward the ends of the reed, for widening the distribution of the yarns as compared with their position upon the spool, but our invention is equally applicable to a case in which a narrowed distribution of the yarns might be desired, in which instance the offsetting of the reed dents would be the reverse of that shown.

Referring now to Fig. 12, the dents, with the exception of the central portion of the reed, wherein they may be without offset, include said straight upper winding-guide portions 71, intermediate inclined or realigning portions 72, and the lower redistributed or yarn-applying guide portion 73. The dents 70 are preferably equipped with yarn retaining detents or projections 74 as in the previous figures, are of a similar relatively wide blade-like construction, and are formed with tangs or mounting portions 75 for individually removable assembling or disassembling them in the reed.

In Figs. 11 and 12, as compared with Figs. 15 and 16, the reed and the transfer comb 53 are shown in their elevated position, after the winding operation, which they assume in applying the transfer comb. During the winding operation, both the comb and the reed are in the normal or lowered position of Figs. 15 and 16, in which only the upper winding-guide portions 71 of the reed dents are in cooperative guiding relation with the yarns, as indicated by the dotted line position of the dents in Fig. 11. The cross bar 25, the yarn table 26, the index 48, as well as the comb holder 54, the lifter cam levers 63 and their pivotal supports 64, as well as other parts not necessary to mention specifically, may be the same as in the previous figures. After winding, the comb and the reed are elevated in unison, so that the offset or intermediate inclined parts 72 of the reed dents first shift the yarns laterally to the dotted line position as in Fig. 14, and cause them to have the desired spacing the same as that of the comb teeth, which then pass up between them.

The mounting of the reed dents, for lifting in unison with the transfer comb, may be by means of a slotted mounting bar such as 33 of Figs. 3 and 4, but we have, in Figs. 11, 12 and 16, illustrated a modified form of mounting. The individual dents are formed with a reduced lower or tang portion 75 and with rear and front shoulders 76, 77 respectively, the latter adapted to seat upon the rear top portion of the comb holder 54, 75

with the fore edge of the tang against the rear wall of said holder. The dents are individually removably held in position upon the holder as by means of an attaching strip or bar 78 adapted to be applied against the rear edges of the dent tangs 75 and to be secured in position as by means of the screws 79. The inner face of this mounting bar may be appropriately slotted as indicated in dotted line at 80 to receive the dent tangs, to retain the dents in the desired position laterally, that is, lengthwise of the reed. The dents are additionally releasably locked, against vertical dislodgement, as by means of a longitudinally extending key 81 received in a rear locking slot 82 formed in each dent.

In the described manner, and as shown in said Figs. 11, 12, 15 and 16, the feature of individual assembly and demounting of the dents, for replacement, redistribution, or other purposes, is preserved as well as that of insuring proper guiding and application of the yarns with respect to the comb. The other novel features, including that of ready identification of any individual dent and of visual demarkation of the dents or series 25 of them, as by the provision of markers, and the other features of Figs. 1 to 10, may likewise be embodied in connection with the form of Figs. 11 to 16.

In order that the reed dents of Figs. 11 and 12, 30 having the offset provisions for redistributing the yarns in the application of the transfer comb, may also be used interchangeably, upon the same or other machines, in cases where such spreading or redistribution of the yarns is desired, the construction of the dents themselves and of their attaching elements as well as the comb holder and associated portions of the machine itself, may be and desirably are arranged for such interchangeability.

40 In the latter case, that is, where no redistribution is desired, the reed is preferably mounted in fixed position upon the machine, independently of the comb holder, so that it is not elevated with the latter. It is nevertheless desirable that the reed dents remain facing in the same direction, that is, with their fore guide portions 70a at the side toward the yarn spool. In such instance, referring now particularly to Fig. 13, the same mounting strip or bar 78, or other similar strip, 45 is shifted to the front wall of the cross bar 25, and the rear shoulders 76 of the dents are set upon the top of said mounting strip, with the rear edges of the tangs 75 against the front wall of the strip. The dents are there held by means of a second or 50 front attaching strip 83, which may also be the same or a similar strip as the member 80 of Fig. 11 and may be similarly slotted as at 84 for positioning the dents laterally. In some cases the same rear locking slot 82 of the dents may be 55 used for locking them vertically, but these rear locking notches, in the arrangement as shown in Fig. 13, become relatively inaccessible. To facilitate the locking of the dents and in order that they may be readily demountable or replaceable merely by the removal of the front strip 83, the dents are preferably provided with a second front locking notch 85 for the reception of a key 81 as in Fig. 11.

70 It is thus apparent, by comparison of Fig. 13 with Fig. 11, that the same individual dents as provided for the redistributing form of Fig. 11 may also be employed in the fixed-reed form of Fig. 13, or of Figs. 1 to 10, without necessitating special forms of dents for the particular installa-

tions, and that the type of installation may readily be interchanged, from that of the lifting and redistributing reed type of Figs. 11, 12 and 14 to 16, to the fixed reed type of Fig. 13 and of Figs. 1 to 10, and the reverse.

Our invention is not limited to the particular embodiments shown and described herein by way of example, its scope being pointed out in the following claims:

We claim,

1. In a tuft-yarn spooling machine, a frame, spool rotating means thereon, a series of flat blade-like members disposed in the manner of a reed, a vertically movable transfer comb holder, and a mounting element extending along and 15 removably associated with the comb holder, said element having a series of spacing formations for individually demountably supporting said reed members for vertical movement in unison with the comb holder.

2. A reed for a tuft-yarn spooling machine, comprising a plurality of blade-like dents, each dent including a main yarn-separating and guiding portion and a mounting portion, and a dent mounting bar having one or more flanges, each 25 provided with a series of spaced holding formations for removably receiving the mounting portions of said dents.

3. A reed for a tuft-yarn spooling machine, comprising a plurality of blade-like dents, each 30 dent including a main yarn-separating and guiding portion and a mounting portion, a dent mounting bar having one or more flanges each provided with a series of spaced holding formations for removably receiving the mounting portions of said dents, each dent having a locking formation, and means releasably engageable with said locking formation to retain the dents in mounted position in their respective holding formations.

4. In mechanism for setting the yarns on tuft-yarn spools for Axminster and like looms, in combination with a frame including a reed support, a reed mounting element comprising an elongated flanged strip, a series of dent-receiving formations distributed predeterminedly along and in a flange of said strip, and a plurality of flat dents removably positioned in said receiving formations.

5. A dent for a reed of a tuft-yarn spooling 50 machine, said dent formed as a flat blade-like element having a yarn guiding portion and a lower mounting portion including an edge recess to receive a locking detent and adapting the dent for demountable reception in operative position, 55 and a laterally deflected yarn-retaining nib on one edge portion of the dent adjacent its upper end.

6. A dent for a reed of a tuft-yarn spooling machine, in accordance with claim 5, wherein a 60 portion immediately above the mounting portion is laterally offset with respect to the yarn guiding portion and is connected to the latter by an inclined portion.

7. A dent for a reed of a tuft-yarn spooling machine, comprising a flat metallic strip-like member including a main blade or yarn-guiding portion, a mounting tang below the main blade, said tang having one or more shoulders for positioning the dent vertically and having a recessed 70 locking formation on at least one edge for the reception of a locking detent, and yarn retaining means projecting laterally of the dent at an upper portion thereof.

8. A dent for a reed of a yarn spooling ma- 75

- chine, comprising a flat metallic strip-like member including a main blade or yarn-guiding portion, a mounting tang below the main blade, said tang having one or more shoulders for positioning the dent vertically and having a recessed locking formation on at least one edge for the reception of a locking detent, and a distinguishing market portion projecting from said main portion.
- 5 10. A reed and reed-support for a tuft-yarn spooling machine, comprising, in combination, a plurality of blade-like dents, each dent including an upright yarn-separating and guiding portion and a mounting portion, a transversely extending element along one edge of the mounting portions of the dents and in holding relation with them, dent spacing means, and a strip removably positioned along the opposite edges of the dents for individually demountably retaining them in 15 operative position, whereby on removal of said strip any dent or a plurality thereof are exposed for inspection, removal or rearrangement.
- 10 11. A reed and reed-support for a tuft-yarn spooling machine, comprising, in combination, a plurality of blade-like dents, each dent including an upright yarn-separating and guiding portion and a mounting portion, a transversely extending element along one edge of the mounting portions of the dents and in holding relation with them, a strip removably positioned along the opposite edges of the dents for individually demountably retaining them in operative position, a locking key extending along the series of dents and engaged with said strip and a 20 cooperating key-receiving formation in the mounting portion of each dent.
- 15 12. In mechanism of the class described, in combination, a frame, spool supporting and winding means, a vertically movable transfer comb holder below and extending transversely of and below the path of the yarns, a series of individually demountable blade-like dents for guiding the yarns during the winding operation, said dents each having a lower mounting portion, and dent attaching and supporting means, said means including a removable retaining strip and dent spacing means, and being carried by a fixed portion of the machine for demountably receiving said mounting portions of the dents, independently of the comb holder.
- 25 13. In mechanism of the class described, in combination, a frame, spool supporting and winding means, a vertically movable transfer comb holder extending transversely of and below the path of the yarns, a series of individually demountable blade-like members for guiding the yarns during the winding operation, said members each having a lower mounting portion, and mounting means whereby said members are operatively demountably positionable alternatively for vertical movement with the comb holder or in fixed position independently thereof.
- 30 14. In a tuft-yarn spooling machine, a reed comprising a plurality of individually spaced dents of blade-like form, each dent including an upper upright yarn guiding portion, an angularly disposed portion and a lower upright portion, and a mounting portion, a transfer comb holder adapted to be elevated to apply a comb to the yarns, and attaching means for supporting said dents for vertical movement with the transfer comb holder, the upper upright portions of said dents being in the plane of the winding-on yarns 35 in the non-elevated position of said holder, said attaching means including an elongated element providing individual seats for the mounting portions of the dents and means removably retaining the dents in said seats.
- 35 15. In a tuft-yarn spooling machine, a reed comprising a plurality of individually spaced members of blade-like form, each member including an upper upright yarn guiding portion, an angularly disposed portion and a lower upright portion, and a mounting portion, a transfer comb holder adapted to be elevated to apply a comb to the yarns, attaching means for supporting said members for vertical movement with the transfer comb holder, the upper upright portions of said members being in the plane of the winding-on yarns 40 in the non-elevated position of said holder, and alternative means for fixedly mounting said members independently of the comb holder.
- 40 16. In a tuft-yarn spooling machine, in combination, a frame, spool winding means, a yarn-guiding reed intermediate the spool and the yarn supply, said reed comprising an elongated supporting element, a multiplicity of spaced dents, some of said dents carrying readily distinguishable marking elements for visually demarking the desired sections of the reed, said dents, including said marker dents, being individually demountable for replacement and rearrangement, and said supporting element including dent spacing means and a removable retaining member for the dents.
- 45 17. In a yarn spooling machine, a frame, a transfer comb holder extending transversely of the path of the yarns, vertical guideways for the 45 comb holder wherein the holder is movable to and from elevated position, a reed in substantial parallelism with the comb holder, and one or more adjustable blocks 57 intermediate the comb holder and said guideways for variably position- 50 ing the holder longitudinally.
- 50 18. In a yarn spooling machine, a frame, a transfer comb holder extending transversely of the path of the yarns, guide means for the comb holder wherein the holder is movable to and from elevated position, a reed in substantial parallelism with the comb holder, said holder having an elongated seat for a transfer comb, and one or more variably positionable adjusting stops 61 carried by the holder for accurately positioning a comb 60 therein longitudinally and with respect to the reed.
- 55 19. In a yarn spooling machine, a frame, a transfer comb holder extending transversely of the path of the yarns, guide means for the comb holder wherein the holder is movable to and from elevated position, a reed in substantial parallelism with the comb holder, an adjusting element on the comb holder for variably positioning a comb longitudinally with respect to the holder, 70 and additional adjusting means for varying the position of the holder and supported comb with respect to the reed.
- 60 20. In a yarn spooling machine, a frame, a vertically movable holder thereon for a transfer 75

5 comb, said holder comprising a bar extending transversely of the machine, an elongated U-shaped seat in said holder for a transfer comb, of a depth to support the latter with its teeth 5 projecting above the holder, a pocket-like recess at an end of said seat, and a vertically open portion at the corresponding end of said holder and in communication with said recess, to facilitate 10 cleaning of the comb seat.

10 21. In a yarn spooling machine, a frame, a vertically movable holder thereon for a transfer comb, said holder comprising a bar extending transversely of the machine, guides for the holder, means for vertically moving the holder in the 15 guides, a fixed cross piece on the machine spaced from and in parallelism with the comb holder, a series of dents for forming a reed, and means for detachably mounting said dents alternatively along and upon said holder or upon said fixed 20 cross piece.

22. A yarn-setting frame for the tuft-yarn spools of Axminster and like looms, comprising in combination, a frame, spool supporting and rotating means on the frame, a transfer comb holder and means supporting it for movement transversely of the path of the yarns traveling to- 25

ward said spool supporting means, and a yarn-guiding reed comprising a series of dents and positioning means therefor, the construction and arrangement of said holder and its supporting means and of the reed and its dent positioning means being such that the holder and reed may be moved as a unit crosswise the yarn path or by adjustment the holder may be so moved but the reed will remain stationary.

23. In a tuft-yarn spooling machine in accordance with claim 1, the combination therewith of a stationary graduated index member extending along the reed adjacent the lower ends of the exposed portions of the blade-like members, said index member provided with indicia arranged in accordance with a given spacing of said blade-like members, for identifying the individual members of the series or the spaces between them.

24. In mechanism of the class described, in the combination of claim 12, a stationary graduated index member extending along the series of dents and bearing indicia arranged in accordance with the dent spacing means, to assist in identifying the individual dents or the interdental spaces.
